UNITED STATES PATENT OFFICE.

EUGENE W. HAWLEY, OF PHILADELPHIA, PENNSYLVANIA.

LOCKING DEVICE FOR TRUNK DRAWERS.

Application filed February 14, 1922. Serial No. 536,607.

To all whom it may concern:

Be it known that I, EUGENE W. HAWLEY, a citizen of the United States, residing at Philadelphia, county of Philadelphia, and 5 State of Pennsylvania, have invented a new and useful Improvement in Locking Devices for Trunk Drawers, of which the following is a full, clear, and exact description, reference being had to the accompanying 10 drawings, which form a part of this specification.

My invention relates to an improvement in locking means for trunk drawers.

Heretofore it has been known to effect a 15 locking of a bank of drawers in a trunk, such, for example, as a wardrobe trunk, by means of a single lock carried by one of the drawers or by the body of the trunk, it being customary to provide a bar extending along 20 the faces of the drawers, centrally or at their edges, which is anchored or secured to the trunk body and engaged and held in locking position in front of the drawers by the lock above mentioned.

25 My invention is applicable, for example, to a drawer locking device such as is shown and described in the patent to Eugene W. Hawley, No. 1,366,451, dated January 25, 1921, in which are provided a pair of locking bars hinged to the trunk body and adapted to extend along the faces of a plurality of drawers at opposite edges and in such position to be locked by a single lock to effect a locking of all the drawers. Springs are provided which, when the lock is released, operate to cause the bars to turn on their 30 hinges away from the faces of the drawers permitting them to open fully.

Such a structure is open to the serious objection that if, when the trunk is closed, the 40 drawer locking bars are left in open or unlocked position, they, and especially the bar adjacent the free edges of the two sections of the trunk, will tend to jam to the injury 45 of the bars and the trunk body and necessitating the re-opening of the trunk and proper positioning of the locking boss.

By virtue of my invention, the disadvantage pointed out above is eliminated and a 50 structure provided which will insure a proper positioning and locking, if a spring lock is used, of the drawer locking bars by the mere closing of the trunk, without the necessity for preliminarily positioning the 55 bars.

Having now indicated in a general way

the nature, purpose and advantages of my invention, I will proceed to describe, in detail, a preferred embodiment thereof with reference to the accompanying drawings, in 60 which—

Fig. 1 is a front view of a wardrobe trunk embodying my invention, the trunk being partially open.

Fig. 2 is a sectional view of a portion of 65 the trunk shown in Fig. 1, with the locking bars in unlocked position.

Fig. 3 is a detailed cross-sectional view of a portion of the trunk shown in Fig. 1, the trunk being almost closed, the locking bars 70 being in open position.

Fig. 4 is a detail showing method of hinging the locking bars to the trunk.

Fig. 5 is a cross-sectional view on line 5, Fig. 1. 75

Fig. 6 is a cross-sectional view on line 6, Fig. 1.

The trunk of the wardrobe type is composed of the clothes compartment *a* and the drawer compartment *b* hinged to each other. 80 The compartment *b* is divided by a partition *c* and in which are fitted the drawers *d*. The compartment *b* carries trunk locking hooks *e* adapted to enter keeper *f* formed in a strip *g* secured inside the compartment *a* adjacent the outer edge thereof. A strip *g'* is secured within the compartment *a* opposite to the strip *g*.

A pair of locking bars *h*, *h'* are hinged to the sides of the compartment *b* by means of 90 hinges *i* in such a manner as to permit the bars to lie along the front of the drawers, and prevent them from being opened, or to be positioned away from the drawers to permit them to be opened. Springs as *j* are 95 connected with the hinges and tend to keep the locking bars *h*, *h'* in open position, permitting the drawers to be opened.

Each of the bars *h*, *h'* is provided on its inner face with a latch *k* which, when the 100 bars are closed, i. e. positioned to lie along the front of the drawers, enters apertures in a casing *l*, fixed to the edge of the partition *c*, and are engaged by bolts *m*, *m* oppositely actuated by a spring *n* and retracted by 105 means of finger pieces *o*, *o*, which may be locked by means of a lock *p*.

Thus, when the locking bars are moved into position to prevent the drawers from opening they are automatically locked by 110 means of bolts *m*, *m*, which may be released by finger pieces *o* to permit the locking bars

to be moved to open position under the influence of springs *j*.

The locking bar *h* is cut out for the passage of hooks *e* and has positioned on its outer surface adjacent its upper end a stop *q* which, when the bar moves to its open position, contacts with the batten strip *r* of the trunk when the bar has moved sufficiently to permit the drawers to open.

10 A cam *s* is secured to the outside of bar *h* in line with the partition *c* and is adapted when the trunk is closed to contact with the face *t* of a bevelled recess provided in the strip *g*.

15 The bar *h'* is provided with a lateral extension *u* in line with casing *c*, which may be similar to cam *s*, and which, in the closing of the trunk, contacts with the strip *g'* and acts to cause the bar *h'* to turn on its hinges 20 into closed position.

In operation, assuming the trunk to be open and the locking bars *h*, *h'* in open position: If the trunk be now closed, the cam *s* on bar *h* will contact with face *t* of the 25 bevelled recess in the strip *g* and further closing of the trunk will cause the bar *h* to be moved on its hinges toward its closed position until the edge of the strip *g* engages with the bar. The final closing movement 30 will cause the bar to move into fully closed position when its latch *h* will be automatically engaged by one of the bolts *m*.

During the closing movement, the extension *u* on bar *h'* engages the strip *g'* and the bar *h'* is moved into closed position.

It will now be observed that stop *q* fixes the open position of the bar *h* so that when the trunk is closed the bar will be moved through the medium of cam *s* rather than 40 jammed as heretofore, while at the same time, as a result of the positioning of the bar by the stop, the cam may be made in such form as not to interfere with the opening of the drawers when the bar is in open position, nor with the closing of the bar or the 45 trunk, when the bar is moved into closing position.

Having now fully described my invention, what I claim and desire to protect by Letters Patent is:

1. A wardrobe trunk having two compartments hinged to each other along one edge, a plurality of drawers slidably mounted in one of the compartments, a drawer locking 55 bar hinged to the drawer compartment at the edge opposite the edge having the hinges connecting the two compartments, means to limit the movement of the bar away from the drawers, and cooperative cam means on the

bar and the other compartment arranged to 60 swing the bar toward the drawers when the compartments are moved toward each other to close the trunk.

2. In a two-compartment wardrobe trunk, a series of drawers in one compartment, an 65 upright bar swingable on a vertical axis into and out of the plane of the drawer fronts to lock the drawers from withdrawal and away from said plane to permit withdrawal, cooperating cams on said bar and 70 the other compartment whereby the closure of the trunk effects an engagement of the cams and a movement of the bar toward locking position, means operating when the trunk is open to swing the bar away from 75 the drawers, and means to arrest the last named movement after the bar has swung sufficiently far to allow the drawers to be pulled out but before it has moved beyond an acute angle relation with the plane speci- 80 fied.

3. In a two-compartment wardrobe trunk, having a plurality of drawers slidable in one compartment, a vertical bar at one side of such compartment adapted to swing into 85 and out of position to hold the drawers from withdrawal, means tending to swing the bar into unlocking position, a cam rigid with the bar engageable by the other compartment as the latter is swung toward closed position, 90 and means to arrest the outward movement of the bar substantially before it reaches a position at right angles to its locking position, whereby the displacement of the cam from the plane of the bar may be relatively 95 slight while insuring the avoidance of a binding action between the second compartment and the bar.

4. A wardrobe trunk having a compartment, a plurality of drawers slidably mounted therein, a closure for said compartment, a drawer locking bar hinged to said compartment adapted to swing toward and away from said drawers, a lock adapted to secure said bar in front of the drawers, a spring 100 tending to move said bar away from the drawers, a stop carried by said bar adapted to cooperate with the compartment to limit the movement of the bar away from said drawers, and a cam carried by said bar 110 adapted to cooperate with said closure in the closing of said compartment to swing said bar toward said drawers.

In testimony of which invention, I have hereunto set my hand, at Philadelphia, Pa., 115 on this 13th day of February, 1922.

EUGENE W. HAWLEY.
